UNITED STATES PATENT OFFICE.

RUFUS GREENLIEF ELLSWORTH, OF NORTHCOTT, KANSAS.

BALING-PRESS FOR HAY, &c.

SPECIFICATION forming part of Letters Patent No. 433,857, dated August 5, 1890.

Application filed October 1, 1889. Serial No. 325,668. (No model.)

To all whom it may concern:

Be it known that I, RUFUS GREENLIEF ELLSWORTH, a citizen of the United States, and a resident of Northcott, in the county of Anderson and State of Kansas, have invented certain new and useful Improvements in Baling-Presses for Hay, &c.; and I do hereby declare that the following is a full, clear, and exact description of the invention, which will enable others skilled in the art to which it appertains to make and use the same.

My invention relates to baling-presses; and it consists, essentially, in providing a construction which will not only possess the advantage of effecting a most thorough pressing of the loose hay, whereby greater compactness is attained, but also in providing a device by means of which the side feed-door is automatically opened and closed on each reciprocation of the follower; and with these and other objects in view it consists in the improved construction and combination of parts, as hereinafter more fully pointed out and described.

In the accompanying drawings, forming part of this specification, Figure 1 is a perspective view of my device complete, showing the door in an open position. Fig. 2 is an enlarged detail view of the door, showing the spring-catch thereon. Fig. 3 is a horizontal sectional view of the press. Fig. 4 is a longitudinal vertical sectional view of the same. Fig. 5 is an end view, in perspective, showing the sweep removed; and Fig. 6 is a perspective view of the under side of the sweep.

Similar letters of reference are used to designate corresponding parts throughout the entire specification and several views of the drawings.

Referring to the drawings, the letter A indicates the frame or body of my improved press mounted upon suitable wheels B. This body or frame is divided into a press-box C, provided with a suitable side feed-opening c and a rear bale-chamber D. The bottom of the press-box is extended forwardly and provided with a bifurcated end E. A shaft F is journaled in bearings upon this extended end, said shaft carrying a bell-crank G, one of the members G thereof be-

ing connected to a follower or plunger H, which slides within the press-box, by means of arms or links g g, the inner ends of said arms being pivoted within a socket g' in the follower. One of the arms formed by the bifurcated end E is provided with an end slot or recess I, and centrally pivoted therein is a vertical arm J, having the upper end beveled inwardly and adapted to engage a beveled shoulder or lug g² upon one of the links g.

A door L is suitably journaled upon a vertical shaft M, located at one end of the feed-opening c, said shaft being extended downwardly and terminating in a crank m. To this crank is attached a rod N, the other end of said rod being secured to the lower end of the vertical arm J. The crank m has also secured thereto a spring O, which extends rearwardly, and is secured to the under side of the body of the press.

Suitably pivoted to one of the side pieces of the frame is a horizontal rod P, the inner end thereof having secured thereto a chain or equivalent Q, while the opposite end of said chain is attached to the follower or plunger. A similar chain R is secured to the outer end of the pivoted horizontal arm, and the rear end of said chain is secured to a spring catch S, located upon the outer side of the door L. This spring bolt or catch is adapted to pass into a recess t in the vertical portion of a laterally-extending feed-table T. It will thus be seen that when the follower is reciprocated by the means hereinafter explained and moves inwardly the inner end of the pivoted horizontal arm is likewise moved inwardly by reason of the connecting-chain, while the outer end of said arm is thrown forward, thus causing the chain secured to this end to be drawn taut and consequently releasing the spring-bolt, the retraction of the spring O at the same time throwing the door open by acting upon the crank m and forcing the upper end of the vertical arm J forward by means of the rod N, connecting the lower end of the same with said crank. As will appear more fully farther on, it will be seen that the opening of the door is effected only after the follower has reached its innermost limit, so that the door remains closed while the follower is moving inward and pressing the hay, so as

to obviate all danger of the latter being forced out, which would be the case if there were no means provided for closing the door during the operation of pressing. As stated, 5 however, the chain connecting the inner end of the horizontal pivoted arm is only drawn taut enough to effect the opening of the door when the follower has reached its extreme inner limit. After this point is reached the follower 10 of course rebounds, and when it reaches its extreme forward or outer limit the beveled lug or shoulder on one of the connecting-links hereof engages the upper end of the vertical arm J and carries the same rearward, 15 thus forcing the lower end forward, or in opposite direction. As the lower end is connected to the crank of the door by means of the rod N, the latter necessarily turns the crank of the shaft upon which the door is 20 mounted, and, overcoming the resiliency of the spring, forces the door inward. Of course after the upper end of the vertical arm J is carried forward a certain distance it becomes disengaged from the shoulder or lug of the 25 bell-crank links or arms, and again resumes its normal position. This operation is automatically repeated as the follower is reciprocated, providing a convenient means for the opening and closing of the door at the most 30 desirable moments—that is to say, opening the door when the follower is on its outward stroke, so that the hay may be inserted, and closing the door when the follower begins to press against the hay, thus preventing the 35 same from being forced out of the feed-opening.

Running through a suitable keeper U, secured to a rod V, is a rope or chain W, which connects at its inner or rear end with the 40 lower member or arm G² of the bell-crank lever. In order to obtain greater strength and security, I connect the ends of the upper and lower members of the bell-crank by means of a metallic strip X. Secured to the inner 45 end of the rod V and extending beneath the bifurcated bottom piece of the press-box is a metallic spring-plate Y, while near the forward end of said rod is secured a cross-bar Z.

The letter A' indicates a segmental arm-guide, one end thereof being secured to the cross-bar Z, while the other end is secured to the forward end of the rod V, and is then inclined downwardly to a slight degree and turned over or bent, so as to form a pocket. 50 (Indicated by the letter a'.) An arm B' is pivoted to the center of the cross-bar by means of a bolt C', the other end of said arm being adapted to rest upon and be guided by the segmental guide-arm. The rope or chain W, 55 after passing through the keeper U, is then passed through a keeper D', secured to the cross-piece Z, and is finally secured to the end of the pivoted arm B'. Pivoted above the arm B' is a sweep E', turning upon the bolt C', upon which the arm is also pivoted. This sweep is provided with a cross-bar F', located 60 slightly to one side of the pivotal point, the

ends of said cross-bar, as well as the end of the sweep proper, being provided with depending bolts G³, which are designed to engage 70 with the pivoted arm when the sweep is revolved. With each third throw of the sweep the arm B' is carried in an arc of a circle through the medium of the depending bolts until it reaches the inclined or downwardly-extending pocket of the segmental arm-guide, 75 when, by reason of coming in contact therewith, and owing to the inclination of the same, it is released from engagement with the bolt and is caused to return to its normal position by the pressure of the metallic spring-plate Y, accelerated by the rebound of the hay after pressure upon the follower, causing the latter to move outward and slackening the tension of the chain W. This pressure 80 of the spring-plate and rebound of the hay also causes the lower member of the bell-crank to pass upwardly between the metallic arms or links g g, thus drawing the follower outward to its extreme limit until the shoulder or lug thereof engages with the beveled upper end of the vertical arm J. As the sweep is further revolved, the other depending bolts will likewise engage the pivoted arm in turn, thus providing for three inward and 85 outward movements of the follower upon each revolution of the sweep. It will also be noticed that when either of the series of depending bolts engages the pivoted arm and causes the same to be carried forward the 90 rope or chain connecting the same with the lower member of the bell-crank will be drawn taut, and, as the arm is carried still farther, the lower member of said bell-crank is drawn 95 downward into the bifurcated end of the press-box, thus causing the inward movement of the follower or plunger within the press-box. Of course the moment the pivoted arm is released and returns to its normal position the rope or chain is necessarily made slack, 100 when the metallic spring-plate bearing upon the lower member of the bell-crank, as previously stated, forces the same upwardly, and consequently causes the outward movement 105 of the follower.

My invention possesses the advantage of providing a full-circle sweep that is mounted without the necessity of bridging for the animal to pass over.

Having thus fully described my invention, 110 what I claim as new, and desire to secure protection in by Letters Patent of the United States, is—

1. The combination of a baling-press, a follower working within the press-box, a bell-crank lever, links connecting the upper arm or member of the bell-crank lever with the follower, a sweep provided with a series of depending bolts, a pivoted metallic arm which the depending bolts engage and release, and a rope secured to the pivoted arm and to the lower member of the bell-crank lever, substantially as set forth.

2. In a baling-press, the combination of a

press-box provided with a suitable side feed-opening and having a forwardly-extending bifurcated portion, a bell-crank lever journaled in said bifurcated portion, a follower provided with a socket or recess, links or arms connecting the follower with the upper member of the bell-crank lever, a metallic spring-plate, the upper end thereof adapted to bear against the lower member of the bell-crank lever and cause the outward movement of the follower, a base-piece, to which the lower end of the metallic spring is secured, a sweep, and a rope for connecting the sweep with the bell-crank lever, substantially as set forth.

3. The combination, in a baling-press, of the press-box and follower, the bell-crank lever, links connecting the bell-crank lever with the follower, a metallic spring-plate, the upper end thereof adapted to bear against the lower member of the bell-crank lever and cause the outward movement of the follower, a base-piece to which the lower end of the spring-plate is attached, said base-piece being provided with a cross-strip, a segmental arm-guide provided with a downwardly-extending end pocket, one end of said arm-guide being connected to the cross-strip of the base-piece and the opposite or pocket end attached to the forward end of said base-piece, a pivoted metallic arm provided with the upwardly-extending lug, a sweep pivoted above the metallic arm by the same pivot-bolt, said sweep being provided with a cross-piece, depending bolts upon the ends of the cross-piece and sweep proper, and a rope secured to the pivoted arm and to the lower member of the bell-crank lever, substantially as set forth.

4. In a baling-press, the combination of a press-box provided with a suitable feed-opening and having an extended bifurcated portion, a bell-crank lever pivoted within said bifurcated portion, a follower, connecting links or arms, one of said arms being provided with a beveled shoulder or lug, a ver-

tical arm mounted within a slot in one of the arms formed by the bifurcated portion of the frame, a vertical shaft within the feed-opening terminating in a crank, a door mounted upon said shaft, a rod connecting the crank with the lower end of the vertical arm, and a spring having one end secured to the crank of the vertical shaft and the other end secured to the rear of the frame, substantially as set forth.

5. In a baling-press, the combination of a press-box provided with a suitable feed-opening and having an extended bifurcated portion, a bell-crank lever pivoted within said bifurcated portion, a follower, connecting links or arms, one of said arms being provided with a beveled shoulder or lug, a vertical arm mounted within a slot in one of the arms formed by the bifurcated portion of the frame, a vertical shaft within the feed-opening terminating in a crank, a door mounted upon said shaft, said door being provided with a suitable spring-actuated bolt or latch, a feed-table extending laterally from the frame of the machine and provided with a suitable recess for the reception of the end of the bolt, a rod connecting the crank with the lower end of the vertical arm, a spring having one end secured to the crank of the vertical shaft and the other end secured to the rear of the frame, a horizontally-pivoted arm, a chain connected to the inner end of said horizontally-pivoted arm and to the follower, and a chain connecting the spring-bolt with the outer end of the horizontally-pivoted arm, substantially as set forth.

In testimony that I claim the foregoing as my own I have hereunto affixed my signature in presence of two witnesses.
